C. A. HUMPHREYS

KEY CASE

Filed July 31, 1924

26 Inventor:
Charles A. Humphreys.
By Cheever & Cox Atty's

UNITED STATES PATENT OFFICE.

CHARLES A. HUMPHREYS, OF CHICAGO, ILLINOIS.

KEY CASE.

Application filed July 31, 1924. Serial No. 729,209.

My invention relates to key cases designed for carrying door keys and keys for lockers, vault boxes, etc., such cases being commonly made of leather for enclosing the keys and making it convenient for the owner to carry them in his pocket. Leather key cases are commonly known, but as heretofore constructed they do not long retain their shape, and one of the objects of my invention is to provide a case which shall be light and yet be so constructed that it will preserve its outline for an indefinite period. Another object is to produce a case of great durability and one which will make it almost impossible, short of complete destruction of the case, to tear the key hooks away from the envelope in which the keys are contained. Another object of the invention is to construct the case in the first instance in the form which is naturally assumed when in the wearer's pocket, thus eliminating the tendency of the pocket to change the outline of the case as a result of the wear. Still another object of the invention is to provide means for segregating some of the keys from the others whereby the keys which are least used will be kept separate from those which are most commonly used, thus enabling the user to quickly select the key or keys which he uses most frequently. Still another object is to provide simple and efficient means for performing the dual function of keeping the key hooks spaced from each other and securing the frame to the envelope. A further object of the invention is to provide an advantageous form of blank which will be economical in the use of leather and will at the same time lend itself to economical manufacture and assembly. Other objects will become apparent as the description proceeds.

I obtain my objects by the construction illustrated in the accompanying drawings in which

Figure 1 is a perspective view of the case closed, and

Figure 2 is a perspective view of the case open.

Figure 3 is a view of the blank from which the case is made.

Figure 4 is a vertical section of the case showing one of the key retainers in open position.

Figure 5 is a perspective view of the metallic frame of the case.

Like numerals denote like parts throughout the several views.

First referring to the blank—this is usually of leather and has a central portion or back 10 bordered laterally by two flaps 12 or cover pieces 12 and at the top and bottom by flaps or extensions 14 and 16 respectively. The two flaps 12 are provided with parts 17 and 18 of a snap fastener by which the case may be kept closed when in the pocket of the wearer. A quadrilateral frame 20 is of approximately the same outline as the back 10 of the case but slightly smaller so that the flaps 12 will readily close over it. This frame is roughly in the form of a keystone, the upper part 22 being somewhat wider than the lower part 24. The advantage of this will be herein-after explained.

The frame is secured to the back by means of the flaps or extensions 14, 16 which are folded inward over the horizontal parts 22, 24 respectively and secured by rows of stitching 25 and 26 respectively. These rows are located on either side of the respective frame parts, and are stitched through the back of the case with the result that the case is firmly secured to the frame across the entire top and bottom, thus effectually preserving the outline of the case. At the same time the sides of the frame are left free for supporting the key retainers 30 which will be again referred to.

The flap 14 has a plurality of spaced apertures 32 through which the key hooks 34 engage and are suspended from the upper part 22 of the frame. The material between these apertures serves as spacers for the hooks. It will be observed that as a result of this construction the weight of the key hooks does not come upon the leather, which in most key cases causes the case to sag after it has been used for a time, but upon the rigid metallic frame. It will also be evident that as a result of this construction the flap 14 performs the dual function of securing the leather of the case to the frame and spacing the key hooks from each other.

The flaps 30, previously mentioned, are secured to the sides of the frame simply by folding a portion of the material around the frame and then applying one or more rows of stitching 40. This forms a simple and efficient means for securing the flaps

30 to the frame in such manner that they may readily swing open and closed. Their function is to overlie the keys least frequently used. These flaps are provided with a snap fastener 44 by which they may be held in closed position.

It is desirable to employ the central aperture 34 for a ring 46 by which the case may be suspended from a chain. This ring passes 10 around the upper part 22 of the frame and will, of course, be retained in central position in the case by the material of flap 14 located on either side of it.

It will be noted that in this the preferred 15 construction the frame 20 is not entirely closed but has an opening 48 at the center of the lower member 24. This has two advantages. First, it makes it possible to employ merely a bent wire for the frame, and 20 second, it affords a place where the chain ring 46 and key rings 34 may be slipped onto the frame.

In practice, when the parts of the case are assembled in the manner described and 25 shown the owner attaches his keys to the various key hooks in the well known manner. Most persons have two or three keys which they use very often, and others which they use seldom. For example, a house door 30 key is commonly used many times a day. The owner of one of my cases will select these keys most frequently used, and will close the flaps 30 underneath them, thus leaving them free in the manner illustrated 35 in Figure 2. The result is that these frequently used keys may be selected automatically or nearly so, thus enabling the owner to obtain the key desired even in the dark.

I have previously called attention to the 40 fact that in the preferred form of device, which I have illustrated, the frame is in the form of a keystone, being smaller at the bottom than at the top. I have found by experience in the manufacture and use of key 45 cases that more space is required for the heads of the keys than for the shanks thereof with the result that ordinary leather cases tend to become distorted and to assume a keystone shape. This throws the 50 outer flaps out of alignment and mars the appearance of the article generally. With my case by initially forming it in keystone shape there is no tendency for the case to become distorted, and the result is that the 55 case maintains its original configuration even after long use.

Having thus described my invention what I claim as new and desire to secure by Letters Patent is:

60 1. A key case having a rigid quadrilateral

marginal frame, key hooks suspended from the upper part of the frame, and a flap secured to one of the sides of the frame within the case for normally overlying the keys least frequently used.

65

2. A key case having a quadrilateral rigid marginal frame, an envelope enclosing the frame, the envelope including a back secured to the frame to prevent the back from losing its proper outline, key hooks suspended from the top of the frame, and flaps secured to the sides of the frame for overlying the keys which are least used.

70

3. A key case having a wire frame in the form of a keystone, wider at the top than at the bottom, an envelope for enclosing the frame and contents, said envelope having a back secured to the frame and being of the same shape as the frame and having flaps for closing the front, key hooks suspended from the upper part of the frame, and means for holding them in spaced relation laterally.

75

4. A key case having a quadrilateral frame of wire, an envelope enclosing the frame, key hooks suspended from the upper part of the frame, the frame having an opening in the bottom through which the key hooks may be threaded onto the frame, and a strip stitched to the envelope and overlying the bottom of the frame to secure the envelope to the frame and at the same time cover the opening in the frame.

80

5. A key case having a quadrilateral frame, an envelope secured to it and adapted to cover it, the envelope having flaps at the front whereby the contents may be exposed, means cooperating with said frame for suspending the keys from the upper edge of the case, and inner flaps pivoted to the side members of the frame whereby when closed they may cover certain of the keys and permit others to lie outside of them for ready use.

85

6. A key case having a quadrilateral wire in the form of a keystone, wider at the top than at the bottom, an envelope for enclosing the frame and contents, said envelope having a back secured to the frame and being of the same shape as the frame and having flaps for closing the front, key-suspending devices suspended from the upper part of the frame, and additional flaps pivoted to the sides of the frame at the lower portion thereof inside of the envelope for retaining the keys most seldom used.

90

In witness whereof, I have hereunto subscribed my name.

CHARLES A. HUMPHREYS.
